UNITED STATES PATENT OFFICE.

ROBERT R. MOFFITT, OF LAMAR, COLORADO.

GRAIN-CAR DOOR.

1,271,347.

Specification of Letters Patent. Patented July 2, 1918.

Application filed April 20, 1917. Serial No. 163,461.

To all whom it may concern:

Be it known that I, ROBERT R. MOFFITT, a citizen of the United States, residing at Lamar, in the county of Prowers and State 5 of Colorado, have invented certain new and useful Improvements in Grain-Car Doors, of which the following is a specification.

This invention relates to grain car doors.

One of the main objects of the invention

- 10 is to provide a door of the character stated of simple construction and operation which may be produced at relatively small cost. A further object is to provide a door which may be used with either a steel car or a 15 wooden car and, when used with a wooden car will not necessitate damaging the latter by driving of nails or other securing elements into the door frame. A further object is to provide a door which may be 20 quickly and easily applied without necessitating any extensive alterations in the construction of the door frame, and may, for this reason, be readily used in connection with cars of standard construction. A still 25 further object is to provide a door which may be readily raised so as to permit the escape of grain when unloading the car. Further objects will appear from the detailed description.

30 In the drawings:—

Figure 1 is a central sectional view taken through a door constructed in accordance with my invention as applied;

Fig. 2 is a front view of the door as applied;

Fig. 3 is a detail perspective view of the bottom plate of the door;

Fig. 4 is a similar view of the securing strap for the door post and the upper end 40 portion of the post showing the cooperating slot and finger of the clamp and post for preventing end play of the latter.

The car A is provided with the usual door-way or opening B which is surrounded 45 by the door frame C of standard construction. A socket 1 is secured in the floor D of the car at the transverse center of the door opening. This socket receives the lower end of a vertical door post 2 the upper 50 end of which fits snugly in the hook 3 of a securing strap 4 which is provided with the integral shank 5 disposed in a plane at right angles to the plane of the hook and secured to the top beam E of the door frame 55 by screws 6. As will be noted from Fig. 4 of the drawings, the free end of hook 3 is

turned in substantially at right angles to provide a finger for engagement into a recess or slot formed in the upper portion of post 2 so as to prevent rotary movement of the post when in operative position. By this means, the door post may be quickly and easily secured in position so as to extend across the door opening at the transverse center thereof, and when desired, may 60 be readily removed by forcing the upper end of the post inward so as to force it out of the hook 3, which is open and resilient for this purpose, the socket 1 being slightly 65 larger in interior diameter than the exterior diameter of the post 2 to permit inward movement of the upper end of the post, or the securing hook 4 may be removed from 70 the door beam E.

This post serves to support the door 7 and 75 to prevent inward movement of the same. Door 7 is composed of a plurality, in this case three, of plates 8, 9, and 10. These plates may be formed by rolling out of sheet metal of suitable thickness, and are of such 80 length as to extend across the door opening, the ends of the plates projecting a short distance inside of the side beams of the door frame, as in Fig. 2 of the drawings. Plate 8 is turned inward at right angles at 85 its lower edge, as at 8^a, and is then bent down at right angles to provide a depending flange 8^b, this flange being set in from the body of the plate a distance corresponding to the thickness of the plate. This depending inset flange 8^b forms a recess at the bottom of plate 8 extending the full length thereof which snugly receives the upper edge portion of plate 9. The lower edge portion of plate 9 is similarly bent to provide a depending flange 9^a which forms a longitudinally extending recess to receive the upper edge portion of bottom plate 10. By this 90 means, the plates may be secured in interlocking engagement so as to produce practically a unitary structure which is comparatively light but very strong and rigid, the flanges 8^b and 9^a also serving to provide 95 tight closures between the plates of the body of the door so as to effectually eliminate all 100 danger of leakage of the grain.

The bottom plate 10 is provided with two apertures 11 and 12 which are disposed equidistant from the longitudinal center of the plate and in substantially the plane of the 110 transverse center of the plate. These apertures receive the inner ends of the arm of a

U-clip 13. This clip fits snugly about post 2 with its arms extending through the apertures 11 and 12 so as to project beyond the inner face of the plate, each arm of the clip 5 being threaded to receive a securing nut 14. By this means the plate is detachably secured to the post 2, the outer face of the plate fitting tightly against the inner face of the side beam of the door frame, the post 10 2 being so positioned as to have its innermost face in the same plane as the inner faces of the side beams of the door frame. The center plate 9 is similarly secured to the post 2 by a U-clip 15, the top plate 8 being secured to the post by a clip 16. The clips 15, 13, and 16, while serving to effectually prevent inward movement of the door, permit the door to be raised vertically by means of a suitable instrument inserted under the 20 same.

The bottom plate 10 has its lower edge portion bent at right angles to provide the horizontal shoulder 17, and then turned downward at right angles to form the depending 25 flange 18. This flange is provided with two recesses or pockets 19 positioned a short distance from each end of the plate and equidistant from the longitudinal center thereof. When it is desired to raise the door, a suitable instrument, such as a pinch-bar may be 30 inserted into the pockets 19 and the door may be readily raised by this means. When the grain has been removed from the car the door may be quickly and easily removed, 35 as a unit, by removing the post 2 in the manner previously described or, if desired, each plate of the door may be removed separately from the post, after which the post may be removed.

40 By bending the plates so as to produce the

depending flange at the lower edge of each plate, and the intermediate horizontal arm or shoulder connecting this flange to the body of the plate, I produce, in effect, an angle iron construction at the lower edge of 45 each plate which renders it possible to construct the plates of comparatively light material. As the door plates are mounted in interlocking or overlapping relation, they serve to reinforce each other thus producing a door of light weight well able to withstand the pressure to which it is subjected by the grain contained within the car. 50

What is claimed is:—

The combination with a car body having 55 a door opening and a frame extending about the same; of a socket secured in the floor of said body, an open resilient hook secured to the top beam of the frame in vertical alignment with said socket and provided at its 60 free end with an integral inwardly extending finger, a post having its lower end seated in said socket and its upper end mounted in the hook so as to be detachably secured thereby to the top beam of the door frame, 65 said post being provided in its upper end with a slot to receive said finger so as to secure the post against rotary movement, and a plurality of superposed plates secured to the post and extending across the door 70 opening and having their ends projecting beyond the side beams of the door frame adjacent the inner face thereof.

In testimony whereof I affix my signature in presence of two witnesses. 75

ROBERT R. MOFFITT.
